FREE ORBITAL SURFACE TREATING TOOL

BACKGROUND OF THE INVENTION

This invention relates generally to a free orbital surface treating tool, and more particularly to a motor driven hand tool particularly useful in modifying a surface as for example by sanding or abrading, polishing or buffing.

PRIOR ART

Various types of free orbital motor driven tools are used for grinding, sanding, polishing, and other such kinds of surface treatment operations. In such machines eccentric or orbital motion is sometimes achieved by mounting two shafts in side-by-side relation with a proper distance between centers, and wherein one shaft is laterally displaced with respect to the other in order to allow one shaft and its bearing assembly to swing or move in an eccentric fashion without interference from the other shaft. In such an arrangement, difficulty is encountered when relatively small eccentricity is desired since it is necessary to reduce the shaft and bearing sizes and thereby weaken the structure. A typical example of such a structure is shown in U.S. Pat. No. 2,967,315 dated Jan. 10, 1961.

To overcome the problem of shaft sizes and relative lateral displacement of the axis of the shafts, structures are sometimes used wherein the two shafts are longitudinally displaced as shown in U.S. Pat. No. 2,794,303 dated June 4, 1957. Such structure requires additional length in the orbit drive and produces undesirable balancing problems and large force couples which must be absorbed by the bearings.

Although such machines may function for their intended purposes, they present problems. It is desirable that the freedom of the surface treating medium supporting member to rotate about its own axis and the mechanism by which eccentricity is introduced into the motion of the surface treating medium supporting member be accomplished in the same plane or close to the same plane. Still further, it is desired that the shaft extending from the drive means shall not require reduction in diameter and consequent loss of strength in order to accommodate a second shaft. Still further, it is desired to simplify the structure both as to material used and as to cost of manufacture so that the cost of manufacture may be minimized.

SUMMARY OF INVENTION

The present invention provides a solution to the foregoing problems, and achieves eccentric motion combined with free orbital movement of the surface treatment medium supporting member. With the improved apparatus of the present invention, eccentricity can be accomplished in virtually the "same plane." This allows for minimum overall height of the machine which is of importance in many applications and minimizes problems of bearing loading and balancing. Further, the structure of the present invention allows for greater strength since the diameter of the shaft of the drive means need not be restricted to accommodate a second shaft. The second shaft is eliminated, and the operations necessary in manufacture of the apparatus of the present invention are minimized and simplified. For example, as will be hereinafter more particularly explained, a large bearing is provided which rotates eccentrically and surrounds the main motor drive shaft. This bearing may be pressed onto a retaining shoulder provided in the eccentric member and when so pressed it holds tightly without setscrews or retaining plates.

A driven disc, or surface treating medium supporting member, is directly formed of rubber and is mounted directly over the outer rim of the eccentric bearing by a simple clamping action. The driven disc is provided with a hub or rim which has a sufficient depth in a preferred embodiment to allow it to extend slightly beyond the width of the bearing. When clamped in this position, there is sufficient deformation of the resilient rubber material to effect an overlapping of the edge of the bearing. This overlap assists in mechanically locking the disc firmly on the bearing until the compressive stress is

released. The rubber disc may be formed with a hardness selected to provide the best operating characteristics for the particular work intended to be performed. For example, the disc may be formed of relatively hard or soft material in the range from 70 on the Shore D scale to 90 on the Shore A scale. The driven disc may be formed of any other material, e.g. plastic, aluminum, etc., although for convenience an elastomeric material is preferred.

10 A suitable housing for the motor may be provided and fitted with handles for manual operation, or with an upwardly extending rod and handle for use by an operator in a standing position. For convenience, the invention will be described with reference to an electrically driven apparatus of the hand tool type, it being understood that the principles of the invention may be embodied in many other forms of tools. The devices of this invention may also be used in multiples in a single tool; for example, a double or triple head floor polishing or grinding tool with suitable coupling means for driving plural heads. While electric motor drive means are preferred, it will also be understood that the invention may be embodied using pneumatic drive means or any other suitable driving mechanism.

25 Briefly, stated, then, this invention is in a free orbital, surface treating tool comprising in combination drive means including a shaft member rotatable about its longitudinal axis. To the shaft is secured by any suitable means an eccentric member rotatable with the shaft. A support for a surface treating medium, e.g. a disc for supporting a buffing material, is provided for attachment to the eccentric. To this end, the support is provided with a recess dimensioned to surround a peripheral portion of the eccentric. Bearing means coact between the eccentric and the recess to allow the support to rotate freely relative to the eccentric.

OBJECTS OF THE INVENTION

It is an important object of this invention to provide a novel and improved free orbital eccentric surface treating tool 40 which is particularly suited for use in performing surface treating or modifying operations such as sanding, grinding, buffing or polishing.

A still further object of this invention is to provide a novel and improved apparatus which reduces the number of parts and part complexity to provide a simple and rugged tool.

Another important object of this invention is to provide a novel and improved free orbital eccentric surface treating tool in which the counterbalancing means for the eccentric is advantageously disposed with respect to access and with respect to minimizing forced couples on the mechanism.

Further objects and advantages of the invention will appear from the following description and the annexed drawings wherein:

55 FIG. 1 is an elevation, partially in section and partially in phantom showing a preferred embodiment of the present invention, and having a shroud or housing therefor fitted with appropriate laterally extending handles to facilitate manual operation, the shroud being shown in phantom.

60 FIG. 2 is a perspective view of an eccentric and counterbalance useful in accordance with the present invention, and shown in cross section in FIG. 1.

65 Referring now more particularly to FIG. 1, there is here illustrated a preferred embodiment of a free orbital eccentric surface treating tool embodying the present invention. This tool includes an electric motor 10 having, at least one end thereof, an accessible drive shaft 12 which may be conveniently provided with threads 14, and having a shoulder 16 adjacent the bearing housing 18. It is to be understood that 70 while the electric motor shown in the annexed drawings is provided with a projecting shaft, other structures may be employed; for example, the shaft end could be flush with the motor housing and by being provided with internal attachment means, e.g. threads or slot and key means, enable attachment of a driven member which itself is provided with a projecting

shaft. Special treatment of the shaft portion 12 is not required and reduction in diameter to accommodate other parts is rendered unnecessary as will be explained below. Although any suitable means for attaching the housing or shroud 20 to the motor may be employed, in the embodiment shown in FIG. 1, studs 22 extending rearwardly from the motor 10 and fitted with finishing nuts 24 may be used to cooperate with circumferentially disposed mounting bosses 26 to retain the housing or shroud 20 on the apparatus. In the device illustrated, three such mounting bosses 26 disposed at 120° intervals have been found to be satisfactory. As indicated above, the shroud or housing 20 may be of any suitable configuration as may be determined by the operation to be performed. In fact, in some embodiments of the invention, a series of interchangeable shrouds may be provided to better accommodate the apparatus to different surface treating operations.

The characterizing components of the present invention are shown in section in FIG. 1. There is provided an eccentric body 28 which may be formed of a suitable cast metal, e.g. iron or aluminum. The eccentric body 28 is provided with a bore 30 which may in turn be provided with internal threads 32 for fastening coaction with the threaded projecting portion of the drive shaft. Other than thread means, any suitable means of securing the eccentric body 28 to the drive shaft portion 12 may be employed such as, for example, a key slot and key, or a shrink-fit of one part to the other. With the thread fastening means or the key-slot fastening means, the eccentric 28 may be replaced with a different eccentric body having a different degree of eccentricity. The feature of interchangeability renders the present apparatus adaptable to a larger variety of surface treating operations in a much simpler fashion than heretofore possible with, for example, the two-shaft devices of the prior art.

FIG. 2 shows in perspective a form of eccentric which is especially suitable for use in the present invention. As shown in FIG. 2, the eccentric member consists of a disc body 28 having a bore 30 radially displaced from the center and extending into the disc body 28 on an axis which is parallel to the major axis of the eccentric body 28. In the embodiment shown, the bore 30 is provided with threads 32 for mating coaction with the threads 14 of the drive shaft 12. In order to balance eccentric body 28 for rotation, counterbalancing means are provided in the form of a counterbalancing mass 34 which is secured to eccentric body 28 by means of laterally extending arm 36. The counterbalancing mass 34 in the embodiment shown is in the form of a segment of a circle, and its mass coupled with the mass of the arm 36 is sufficient to adjust the static balance of the rotating and orbiting system so that its center of mass is located on the axis of rotation through the center of bore 30. The particular configuration of counterbalance mass 34 is desirably, although not essentially, completed in the form of rim 37 which is supported opposite the mass 34 by arm 39 to incorporate an additional safety feature in the devices hereof minimizing injury from rotating mass 34. The remote face 52 (FIG. 1) of eccentric body 28 is provided with a circumferential groove 54.

As shown best in FIG. 1, counterbalancing mass 34 is axially inwardly displaced toward the body of the drive motor 10 because of the configuration of arm 36 which is integral therewith. The mass 34 is displaced so that it orbits in the spacial annulus bounded by the motor bearing housing 18, the forward face 38 of the electric motor 10, and the projection of the sidewall or cover of the motor 10. This utilizes available space efficiently for the accommodation of the counterbalancing mass 34 so that it does not extend beyond the periphery of the housing of electric motor 10. The displacement in an axial direction toward the motor 10, although relatively small, enables easy access to the clamp 40 for ready replacement of the eccentric disc 28 or interchange of surface treating media. At the same time, the displacement is not so great as to introduce intolerable unbalancing forces due to the force couple formed by the axial displacement.

Also shown in FIG. 1 is a support means for a surface treating medium. In the embodiment shown this support means is in the form of a rubber disc 42 having a remote surface 44 and an adjacent surface 46, the terms "remote" and "adjacent" being in reference to the front face 38 of motor 10. Disc 42 is conveniently molded from medium hard to hard rubber and provides a support to which may be secured by any suitable means a surface treating medium of any desired nature. For example, a sandpaper disc may be adhered to the remote surface 44 of disc 42. Alternatively, disc 42 may be partially enveloped in a fabric material of the type commonly used for polishing or buffing. Alternately, disc 42 may be formed from an abrasive composition.

The adjacent surface 46 of disc 42 carries centrally located thereon a recess 48 conveniently formed by upstanding, concentrically disposed rim 50 which is dimensioned so as to surround the lower portion of the eccentric body 28 and the drive shaft 12 carried therein. As indicated above, the remote face 52 of eccentric body 28 is provided with a circumferential groove 54 which is dimensioned to receive the inner race 58 of an antifriction bearing 56 with a press fit. In the illustrated embodiment this simple "press fit" mounting provides the entire coupling between the bearing 56 and the eccentric body 28 but, if desired, other mounting means may be provided.

The disc 42 is removably mounted on the outer race 60 of the bearing by a clamp 40 which applies a releasably compressive stress to the rim 50. Preferably the rim is proportioned when unstressed so that it easily slips over the outer race.

When disc 42 is formed from a rubber material, and clamp 40 is compressed about the outer periphery of rim 50, the resulting compressive force is sufficient to retain body 28 on bearing 56 in such a manner that relative movement in an axial direction is prevented while relative rotation between eccentric body 28 and disc 42 may occur freely. In the preferred embodiment shown in FIG. 1, the axial extension of rim 50 is desirably slightly greater than the axial width of ball bearing 56 so that when clamp 40 is actuated to impose a releaseable compressive stress on rim 50, a circumferential inward bulge 64 of the rubbery material is caused to be formed as a lip 64 behind the bearing race 60. This lip 64 serves to increase the axially outwardly directed thrust loads sustainable by the disc 42 and thereby improve its retention on eccentric body 28.

Of course, any suitable means for securing the surface treating supporting member, for example disc 42 on eccentric body 28, may be employed, that shown in FIG. 1 being, however, a preferred embodiment.

In operation, the apparatus shown in FIG. 1 is provided with a suitable surface treating medium which is secured to disc 42. For example, a buffering pad of generally circular configuration of larger diameter than disc 42 and having a circumferential drawstring or an elastic margin may be secured to disc 42 in the conventional manner. For polishing or buffering, an eccentricity of the order shown in FIG. 1 is convenient. For some grinding operations, a smaller eccentricity may be desired. Accordingly, a suitable eccentric body 28 is selected and secured to shaft 12 as by threading thereon. The eccentric 28 carries a ball bearing 56 press fitted thereto in the groove 54. Disc 42 with or without an attached buffering pad (not shown) is positioned over the outer race 60 of ball bearing 56, and the clamp 40 tightened with a screw driver sufficiently to compressively stress rim 50 to an extent sufficient to retain disc 42 in place on the eccentric body 28, and desirably sufficiently to create a circumferential lip 64 behind the inner marginal edge of outer edge race 60 of ball bearing 56. If the disc 42 is not provided with a surface treating medium, it may be affixed at this time.

Suitable electrical connections are provided so that the motor can be operated by means of toggle switch 68. Laterally extending handles 70 provide a suitable structure for holding the apparatus in position against the surface being buffed. Skirt portion 72 of shroud 20 encloses the mechanism of the forward portion of the motor sufficiently that the operator is not exposed to the rapidly rotating counterbalancing mass 34.

At the same time, access to the clamp 40 is possible so the changing of the disc is easily accomplished.

Although a preferred embodiment of this invention is illustrated, it is to be understood that various modifications and rearrangements of parts may be resorted to without departing from the scope of the invention.

We claim:

1. A free orbital surface treating tool comprising in combination:

- a. electric motor drive means having a shaft member rotatable about its longitudinal axis;
- b. a disc-shaped eccentric member secured to said shaft and rotatable therewith, said eccentric member having a bearing retaining circumferential groove on its remote face, and including an eccentrically disposed shaft receiving bore, a counterbalancing mass supported on an arm in counterbalancing relation to said eccentric member, said arm extending in a radial direction from said eccentric member and supporting said mass at its outer extremity in axially displaced relation, the direction of axial displacement being toward said drive motor;
- c. a resilient elastomeric disc having a planar remote surface for supporting a surface treating medium in juxtaposed relation and an integrally concentrically located circular rim defining a recess on its adjacent surface, said rim being dimensioned to encompass the eccentric member and shaft secured therein;
- d. ball bearing means having an inner race tightly secured in said circumferential groove on said eccentric member and its outer race under radially inwardly directed releasable compressive stress of said rim;
- e. clamping means compressing said rim and coacting with said rim to secure said disc to said bearing outer race.

2. A free orbital surface treating tool comprising in combination, drive means including a shaft member rotatable about its longitudinal axis, an eccentric member secured to said shaft member and rotatable therewith, an antifriction bearing having inner and outer races extending around said eccentric member with said inner race secured thereto, planar

means having adjacent and remote surfaces for supporting a surface treating medium in juxtaposed relation to said remote surface and including on the adjacent surface a recess providing an inner wall surrounding said outer race and at least part of said eccentric member, releasable clamp means operable radially of said outer race and radially aligned therewith to releasably clamp the outer surface of said outer race to secure said planar means to said outer race with said inner wall around said outer race, and a balancing mass carried by said eccentric member movable along a path spaced from but substantially adjacent to said releasable clamp means.

5 3. A free orbital surface treating tool as set forth in claim 2 wherein said planar means includes a flange extending from said adjacent surface and cooperating therewith to provide said recess, and said clamp means are carried by said flange.

10 4. A free orbital surface treating tool as set forth in claim 3 wherein said flange is radially deformable, and said clamp means is a clamp ring surrounding said flange radially deforming said inner wall into tight engagement with said outer race.

15 5. A free orbital surface treating tool as set forth in claim 4 wherein said planar means is free to rotate about said central axis with said eccentric member.

20 6. A free orbital surface treating tool as set forth in claim 5 wherein said planar means including said flange is a unitary body of elastomeric material.

25 7. A free orbital surface treating tool as set forth in claim 4 wherein the axial spacing between said adjacent surface and said balancing means approaches the axial height of said clamping ring.

30 8. A free orbital surface treating tool as set forth in claim 4 wherein said eccentric member is circular in plan shape and includes an eccentrically disposed shaft receiving bore, said shaft extending into said bore with at least a portion thereof surrounded by said flange.

35 9. A free orbital surface treating tool as set forth in claim 4 wherein said balancing means is integrally formed with said eccentric member.

10. A free orbital surface treating tool as set forth in claim 4 wherein said planar means is a circular disc.
